LOUDSPEAKER WITH FLEXIBLE DIAPHRAGM MOUNTING

Filed March 25, 1948

Fig. 1.

UNITED STATES PATENT OFFICE

2,560,379

LOUD-SPEAKER WITH FLEXIBLE
DIAPHRAGM MOUNTINGAlbert L. Witchey, Merchantville, N. J., assignor
to Radio Corporation of America, a corporation
of Delaware

Application March 25, 1948, Serial No. 17,039

10 Claims. (Cl. 179—115.5)

1

This invention relates to acoustic devices, and more particularly to an improved loudspeaker construction having direct radiating diaphragms of the "piston" type.

Heretofore, dynamic type loudspeakers have been constructed having a cone diaphragm suspended at its base from a speaker housing or dishpan support which extends radially beyond the base of the diaphragm, thereby increasing the overall dimensions over that of the diaphragm a considerable amount. In addition to the base suspension, it is necessary to provide (1) another suspension for the center or apex portion of the diaphragm and (2) a means for centering the voice coil with respect to the air gap in the magnet structure. This usually has been accomplished by employing, in addition to the peripheral support for the diaphragm, a separate, corrugated, flexible disc having its outer edge attached to a rigid, adjustable support and its inner edge attached to the center portion of the diaphragm adjacent to the voice coil.

The principal object of my invention is to provide an improved loudspeaker construction using a cone type diaphragm and having smaller overall dimensions than and an improved response over similar prior art loudspeakers.

It is also an object of my invention to provide an improved loudspeaker construction as aforesaid in which the conventional or customary dishpan support for the loudspeaker diaphragm is dispensed with while still providing adequate peripheral support for the diaphragm.

Another object of my present invention is to provide an improved loudspeaker as above set forth in which the same means which supports the inner or apex end of the diaphragm is also utilized to support the outer or peripheral edge thereof.

According to my present invention, I provide a new loudspeaker construction using a cone type diaphragm by eliminating the use of the customary housing or dishpan support for the diaphragm. In accordance with my invention, I provide a single element suspension means for loudspeaker diaphragms which will support the diaphragm both at its base and at the center without extending beyond the outer circumferential limits of the diaphragm. In addition to supporting the diaphragm, the suspension element also functions as a means for centering the voice coil with respect to the air gap provided between the poles of the magnet structure.

The suspension means of my invention, according to a preferred embodiment, consists of a

2

flexible, annular disc having its outer edge attached to the base of the diaphragm and its inner edge attached to the center portion of the diaphragm. The suspension means is supported intermediate its inner and outer edges by an annular ring adjustably carried by the field structure of the loudspeaker, thereby providing a suspension which is disposed entirely within the outer circumferential limits of the diaphragm.

I have also provided a housing for covering the magnet structure and rear portions of the speaker diaphragm. The housing comprises a cylindrical case open at one end and having its closed end attached to the magnet structure, while the edge of the open end is disposed in spaced relation to the outer edge of the diaphragm in such a manner that the diaphragm and housing together form an acoustic chamber.

More specifically, I have provided a new loudspeaker construction which minimizes the overall dimensions thereof, one that provides an improved response, is highly efficient, easy to construct, and economical to manufacture.

The novel features of my invention, both as to its organization and method of operation, as well as additional objects and advantages thereof, will best be understood from the following detailed description of two embodiments thereof, when read in connection with the accompanying drawing, in which

Fig. 1 is a plan view of a loudspeaker constructed in accordance with a preferred form of my present invention,

Fig. 2 is a sectional view thereof, taken along the line 2—2 of Fig. 1,

Fig. 3 is a plan view of the field structure shown in Fig. 2, and

Fig. 4 is a plan view in section of a second embodiment of my present invention taken on a plane through the diaphragm perpendicular to its axis, and illustrating another form of diaphragm support according to my invention.

Referring more particularly to the drawing, there is shown, in Figs. 1 and 2, a loudspeaker having a diaphragm 3, a magnetic field structure 5 for effecting vibration of the diaphragm in accordance with audio frequency currents passing through the voice coil of the diaphragm, and a housing 7 for the elements of the loudspeaker.

The loudspeaker diaphragm 3 is a direct radiating diaphragm of the "piston" type, that is, the type where the central portion is stiffened so that the diaphragm moves as a whole at low frequencies. The diaphragm is made from a material suitable for sound radiation, as, for ex-

ample, a hard finish paper or other fibrous material. The diaphragm comprises a frustroconical center portion 9, and an outwardly flared portion 11 extending from the center portion and curved backward so as to provide an outwardly flared and bowed sound reproducing surface, the portion 11 terminating in a peripheral or outer edge 13. In other words, the diaphragm may be described as substantially semi-toroidal, that is, a surface generated by the rotation of a semi-circular arc about an axis parallel to the radius of the arc which is perpendicular to its cord diameter. Attached to the center portion 9 of the diaphragm as by cementing or otherwise, is a cylindrical coil form 15 which carries a voice coil 17. The diaphragm is also provided with a dust cap 18, preferably of paper, which is attached adjacent the center portion 3 for closing the opening provided by the center portion.

The field structure 5 consists of a U-shaped yoke 21 and an outer pole member 23 attached at its ends to the yoke by welding or other suitable means 25. Within the yoke structure, there is a center core 27 which is constructed in two parts both of which are circular in cross section. The lower or base portion 29 of the core is preferably constructed of permanent magnet material having extremely high retentivity, such as Alnico V, composed of the following elements: aluminum 8 percent, nickel 14 percent, cobalt 24 percent, copper 3 percent, and the remainder iron. The upper portion or inner pole piece 31 of the center core is made of material such as soft iron or mild steel, or other material possessing a high degree of permeability, and has a base or shoulder portion 32 and an upper portion 33.

The center core or pole piece 27 is of sufficient length so that the lower face 34 of the base portion 29 will rest on a flat surface 35 on the bottom of the yoke 21, and the inner pole piece 31 will extend into an aperture 37 in the outer pole member 23. The aperture 37 is of sufficient size so that an air gap 39 is provided between the periphery of the aperture and the inner pole piece 27.

In assembling the U-shaped yoke 21 and the center core or pole piece 27, I have provided a spring clip 41 of the type disclosed in the co-pending application of David H. Cunningham, Ser. No. 632,064, filed November 30, 1945, and now Patent 2,501,031. The spring clip 41 is made of resilient material and has (1) two leg portions 43 and 45 which will rest against the outer pole member 23, and (2) a central portion 47 which connects the leg portions and which bears against the base or shoulder portion 32 of the inner pole piece portion 33 and firmly holds the center core 27 in assembled relation with the yoke 21. The central portion 47 of the spring clip is provided with an aperture 49 through which the upper portion 40 of the inner pole piece 31 extends.

For the purpose of accurately centering the inner pole piece 31 in the aperture 37, I have provided a sheet metal centering disc 51, preferably of brass which is permanently secured to the outer pole member 23 by any suitable means, as by welding 52. The centering disc is also provided with an aperture 53 concentrically disposed with respect to the aperture 37 and through which the inner pole piece 31 may be inserted for centering in the aperture 37.

In order to freely suspend the diaphragm 3 and support the voice coil 17 in its proper relationship to the field structure 5, I have provided a single

element, flexible support or member 55 which consists of an annular, corrugated disc of conventional web material having a high degree of compliance in the axial direction of diaphragm movement and only a limited degree of compliance perpendicular to the axial direction of diaphragm movement. The flexible support or disc 55 has inner and outer edges 57, 59 which are cemented or otherwise suitably attached, respectively, to the peripheral edge 13 of the outwardly flared portion 11 and the inner edge 61 of the center portion 9 of the diaphragm, disposing the peripheral edge 13 and the inner edge 61 in a common plane substantially perpendicular to the axis of the diaphragm. The flexible member 55 is constructed with an intermediate portion 63 between its inner and outer edges 57, 59 which is cemented or otherwise suitably attached to an annular brass ring member 65, and which divides the flexible member into inner and outer portions 64, 66. The annular member 65 is adjustably mounted on top of the outer pole member 23 by two screws 67, 69 which are inserted through holes 71, 73, respectively, in the outer pole member 23. The holes 71, 73 are sufficiently large to permit lateral adjustment of the ring member for centering the voice coil 17 in the air gap 39.

In order to facilitate adjustment of the ring member and to provide access to the screws 67, 69 I have provided holes 75, 77 in the spring clip 41 and holes 79, 81 in the base of the U-shaped yoke 21, the holes 71, 75, and 79 being concentrically aligned and the holes 73, 77, 81 also being concentrically aligned.

The field structure 5 is enclosed in a cylindrical housing 7 open at one end 83. The housing is removably attached to the base of the U-shaped yoke 21 by means of a bolt 85. The housing 7 is constructed so that a space 87 will be provided between the edge 89 of the open end 83 thereof and the peripheral edge 13 of the diaphragm to permit sound waves generated by the back of the diaphragm to be released from the acoustical chamber 91 formed by the diaphragm 3 and the housing 7.

While I have described a preferred form of my invention, it will undoubtedly be apparent to those skilled in the art, that many other forms thereof are possible within the spirit of my invention. For example, as illustrated in Fig. 4, in place of the single element, flexible, corrugated disc 55 used to support the outwardly bowed diaphragm 3, a plurality of radially extending supports 93 may be used to support the diaphragm in a manner similar to the single element support 55. It will, therefore, be seen that, by eliminating the conventional dishpan support and providing an outwardly bowed diaphragm for the loudspeaker, I have provided a loudspeaker having smaller than usual overall dimensions. My improved loudspeaker construction also permits the use of a diaphragm having a larger vibrating surface than has been used customarily in prior art loudspeakers of equivalent size, wherefore the loudspeaker of my present invention is capable of providing an improved response.

While I have illustrated but two modifications of my invention, various other modifications and changes will, no doubt, readily suggest themselves to those skilled in the art. I therefore desire that the particular form of my invention described herein shall be considered as illustrative and not as limiting.

What is claimed is:

1. In an acoustic device, a piston type diaphragm having a frustro-conical center portion and an outwardly flared portion extending from said center portion, driving means operatively associated with said center portion for vibrating said diaphragm, and an annular flexible supporting member disposed between said center and outwardly flared portions attached adjacent the peripheries thereof, said annular flexible supporting member being supported intermediate its inner and outer edges from said driving means.

2. An acoustic device according to claim 1, characterized in that said supporting member has inner and outer edges disposed in a common plane substantially perpendicular to the axis of said diaphragm.

3. An acoustic device according to claim 1, characterized by the addition in said device of a cylindrical housing open at one end, said housing being carried by said driving means and having its open end terminating in spaced radial relation to said outwardly flared portion, and further characterized in that said housing and said diaphragm together form an acoustical chamber.

4. In an acoustic device, a diaphragm of the piston type having a frustro-conical center portion and an outwardly flared portion extending from said center portion, the inner and outer edges disposed in a substantially common plane perpendicular to the axis of said diaphragm, flexible supporting means for said diaphragm connecting said inner and outer edges, said means being fixedly supported intermediate the points of connection to said inner and outer edges, and driving means for said diaphragm operatively associated with said inner edge for vibrating said diaphragm.

5. An acoustic device according to claim 4, wherein said driving means includes a field structure, wherein said diaphragm, said supporting means, and said field structure are provided with a cylindrical housing having one end open, and wherein said housing is carried by said field structure and has said open end terminating in spaced radial relation to said outer edge of said diaphragm.

6. In an acoustic device, a diaphragm having a frustro-conical center portion and an outwardly flared and bowed portion extending from said center portion, said diaphragm terminating in inner and outer edges lying in substantially the same plane perpendicular to the axis of said diaphragm, a flexible support for said diaphragm, said support being connected to said diaphragm at points adjacent to said inner and outer edges, and driving means associated with said diaphragm for vibrating said sound reproducing surface.

7. In an acoustic device, a diaphragm of the piston type having a frustro-conical central portion and an outwardly flared portion extending

from said central portion, flexible supporting means for said diaphragm disposed entirely within the outer limits of said outwardly flared portion and attached to said central and outwardly flared portions, said flexible supporting means comprising a single element, flexible disc fixedly supported intermediate the points of attachment thereof to said central and outwardly flared portions, and driving means for said diaphragm operatively associated with said central portion.

8. In an acoustic device, a diaphragm of the piston type having a frustro-conical central portion and an outwardly flared portion extending from said central portion, flexible supporting means for said diaphragm disposed entirely within the outer limits of said outwardly flared portion and attached to said central and outwardly flared portions, said flexible supporting means comprising a plurality of radially extending flexible supports each of which is fixedly supported intermediate the points of attachment thereof to said central and outwardly flared portions, and driving means for said diaphragm operatively associated with said central portion.

9. In an acoustic device, a diaphragm having a frustro-conical center portion and an outwardly flared portion extending from said center portion, said diaphragm terminating in inner and outer edges lying in substantially the same plane perpendicular to the axis of said diaphragm, a plurality of radially extending flexible supports for said diaphragm, said supports being connected to said diaphragm at points adjacent to said inner and outer edges, and driving means associated with said diaphragm for vibrating said sound reproducing surface.

10. An acoustic device according to claim 9, characterized in that said radially extending diaphragm supports are disposed in circumferential spaced relation to each other about said axis of said diaphragm.
